UNITED STATES PATENT OFFICE.

JOHN P. REINECKE, OF CRAFTON, PENNSYLVANIA.

WATER-HEATER.

1,116,738.

Specification of Letters Patent. Patented Nov. 10, 1914.

Original application filed September 2, 1911, Serial No. 647,345. Divided and this application filed June 6, 1912. Serial No. 701,981.

To all whom it may concern:

Be it known that I, JOHN P. REINECKE, a citizen of the United States, and a resident of Crafton, in the county of Allegheny and State of Pennsylvania, have invented a new and useful Improvement in Water-Heaters; and I do hereby declare the following to be a full, clear, and exact description thereof.

10 My invention relates to instantaneous water heaters wherein the water and gas supply are controlled by the mechanism of the heater.

The object of my invention is to provide 15 a cheap, simple and efficient form of instantaneous water heater whereby the supply of water will regulate the supply of gas admitted to the burner of the same, and such regulation is accomplished by governing means dependent on the temperature of 20 the water in said heater.

To these ends my invention consists, generally stated, in the novel arrangement, construction and combination of parts as 25 hereinafter more specifically set forth and described and particularly pointed out in the claim.

To enable others skilled in the art to which my invention appertains to construct 30 and use my improved instantaneous water heater, I will explain the same more fully, referring to the accompanying drawing, in which—

Figure 1 is a vertical cross-sectional view 25 of my improved instantaneous water heater. Fig. 2 is a vertical cross-sectional view of the water and gas supply valves on the line 2—2 of Fig. 1.

Like symbols of reference herein indicate 40 like parts in each of the figures of the drawing.

My invention herein described is adapted 45 for use with my invention described in my application for a U. S. Letters-Patent, Serial No. 647,345, filed September 2, 1911, and of which this application is a division.

As illustrated in the drawing, my improved instantaneous water heater is made 50 of the ordinary shape and in the ordinary sizes, and is composed of the usual metal casing 1, which is supported by means of legs or standards 2, at the bottom of the same, such legs being adapted to rest on the floor to hold the heater in a vertical position 55 and being secured to the casing 1 in

any suitable manner. Within the casing 2 is an inner jacket 3 which is secured at the upper end of the same to a supporting plate 4, and at its lower end is secured to a like plate 5 and to the flanged portion 6 of the metal casing 1. At the upper end of the casing 1 is a cover 7, and said cover has a hollow interior 8 which is adapted to communicate with the fluid chamber 9, which is formed between the inner jacket 3 and an outer jacket 10, said last named jacket being secured at its upper end to the plate 4 and at its lower end to the plate 5.

Within the fluid chamber 9, which extends entirely around the combustion chamber 11 formed by the inner jacket 3, and spaced equally around the same, is a series of flue tubes or pipes 12, and said tubes are adapted to extend between the plates 4 and 5, and are secured thereto by means of the tube 75 fastening device 13.

In the center of the combustion chamber 11 and supported therein by means of the bracket 19 is a rod 20, and such rod is made of a non-expanding metal and extends upward through an opening 21 in the cover 7, through which it is slidably mounted, while a cover 22 of insulating material is placed around said rod to protect it from the heat from said combustion chamber. The top of the rod 20 is tapered to a point for the purpose to be hereinafter described.

A burner 23 is provided at the bottom of the combustion chamber 11, and such burner is circular in shape and formed integral 90 with the bottom 24, and has openings 25 in the upper face of the same, and such openings are adapted to communicate with the hollow interior 26 of said burner. Into each of the openings 25 in the burner 23 a burner tip or nipple 27 is adapted to be placed, and the upper end of the same extends to a height coincident with the plate 5. The burner 23 and bottom 24 are adapted to be swung downward when desired, and this is accomplished by means of a swivel joint 28 at one side of the same, and the other side of said burner and bottom is secured in its upright position by means of a check or latch 29.

The outer jacket 10 is adapted to form a passageway 30 between the same and the casing 1, and said passageway extends entirely around within said casing and communicates with the tubes 12 by a passage 110

way 31 below the same and formed by the flanged portion 6 of the metal casing 1 and the lower end of the inner jacket 3 so that the products of combustion may pass from the combustion chamber 11 and downward through the tubes 12, thence through the passageway 31 and upward through the passageway 30, at the upper end of which is a flue connection 32 for carrying away such waste products of combustion.

At the top of the cover 7 and at a point near the center of the same is a discharge pipe 34 for drawing fluid from the fluid chamber 9 and through the hollow interior 8 of said cover. The top of the cover 7 is also provided with a post 35, which is at a point substantially near the opening 21 in said cover, and said post has a fulcrum 36 thereon for the purpose of pivoting an arm 37 thereon, while said arm also extends over the pointed upper end of the rod 20 and beyond the same, and engages by its free end 38 with an arm 39 which is pivoted in a fulcrum 40 on the top of the cover 7. A set screw 38' is fixed in the end of the arm 39 and is adapted to bear by the screw end of the same with the free end 38 of the arm 37 for the purpose of regulating the distance between said arms, thereby regulating the temperature of the water. The arm 39 extends beyond the outer casing 1 of the heater and connects with a valve, as herein-after described.

Above the casing 1 is a fluid valve casing 41 which is adapted to be connected to the water supply pipe 41' by its supply opening 42, and said casing has an inverted plunger 43 within the same, said plunger operating between the walls 44 of said casing, while the side walls 45 of said plunger are provided with ports 46 therein and have a packing ring 47 below such ports for preventing the binding of the metal of said walls 44 and the walls 45 of said plunger. The bottom of the plunger 43 is covered with a sheet of wire gauze 48 to prevent any dirt or foreign substance from passing through the valve casing 41 and into the heater. The casing 41 is also provided with an enlarged chamber 48 above the plunger 43, and connecting with said chamber is a passageway 49, which connects with the outlet port 50.

At the bottom of the plunger 43 and at the center of the same is a rod 51 which extends downward, and has a lug 51' on the end thereof and adapted to fit within a link 51^a which is connected to the rod 51^b and such rod extends through the valve casing 41 and through the ordinary stuffing box 52 and enters a fuel valve casing 53 through another stuffing box 54 at the top of the same. The valve casing 53 is provided with an outlet port 55 through which the fuel is adapted to enter the heater by means of the

supply pipe 56 secured therein, and a valve 57 is secured to the end of the rod 51^b extending downward from the valve casing 41 and is adapted to open and close the port 58 within the inner wall 63 of the casing 53 by the operation of the fluid valve 41 above the same. The outlet port 55 communicates with a chamber 59 in which the valve 57 is adapted to operate and a spiral spring 60 is placed around the rod 51 and its movement is limited by the upper part of the casing 53 and the valve 57. At the other side of the valve casing 53 is an inlet port 61 and such port communicates with a chamber 62 which is below and separated from the chamber 59 by the inner wall 63, while a rod 64 enters said chamber from below and through the valve casing 53 and a stuffing box 65, and is secured at its lower end to the arm 39, while the upper end of the same carries a valve 66 which is adapted to control the opening or port 58, as herein-after explained. Around the rod 64 and within the valve casing 53 is a spiral spring 67, which is adapted to rest between the lower wall of said casing and the valve 57 to hold said valve in its raised position.

The fluid supply pipe 41' after connecting to the outlet port 50 of the valve casing 41 passes downward along the side of the casing 1 of the heater and connects with the fluid chamber 9 in order to supply the same with water or other fluid to be heated, while the fluid supply pipe 56 after leaving the valve casing 53 passes downward along the side of the casing 1 in a manner similar to the fluid supply pipe 41' and connects with the swivel joint 28 so that the fuel passing through the supply pipe 56 may enter the hollow interior 26 of the burner 23, and the fluid connection will thus remain intact when said burner is swung downward on said swivel joint. Connecting with the fuel supply pipe 56 and at a point previous to the position of the valve casing 53 is a pilot supply pipe 68 which communicates with said fuel supply pipe and is of a much smaller diameter than the same.

The operation of my improved instantaneous water heater is as follows:—When the water is drawn from the heater through the pipe 34 the pressure of the water supply in the pipe 41' bears against the plunger 43 in the valve casing 41 and raises the same, so that the water passes through the ports 46 and into the chamber 48 and downward through the passageway 49 and the port 50 and through the pipe 41' to the fluid chamber 9 of the heater. As the plunger 43 in the valve casing 41 rises by the pressure of the water, the rod 51 connecting with the bottom of the same will be likewise raised, so that the valve 57 secured to the lower end of the rod 51^b will thus be raised by the connection of said rods by the link 51^a to open

the port 58 below the same and thus allow for the passage of the fuel through such port, since the normal position of the valve 66 on the rod 64 is away from the port 58, 5 as hereinafter explained. When the valve 57 is thus raised from the port 58 in the inner wall 63 of the valve casing 53, the fuel entering through the port 61 from the fuel supply pipe 56, passes into the chamber 62, 10 and thence through the port 58 and into the chamber 59 and out through the port 55 and downward through the pipe 56 and enters the hollow interior 26 of the burner 23 through the swivel joint 28 connecting said 15 pipe and burner. The fuel then passes upward through the openings 25 and the burner tips or nipples 27 and is ignited upon issuing from the top of the same by means of the pilot light which is kept burning constantly. The products of combustion of the fuel pass into the combustion chamber 11 and thence downward through the tubes 12 within the fluid chamber 9, and then through the passageway 31 and into 20 the chamber 30, and is then exhausted into the chimney or flue through the flue connection 32 communicating with the top of said chamber. The products of combustion when at the top of the combustion chamber are in 25 a heated condition and when passing downward through the tubes 12 will become gradually cooled by its contact with the inside of such tubes, the outsides of which are surrounded with the water, and as the hot 30 water rises on account of its being lighter than the cold water, which is admitted at the bottom of the heater, the products of combustion will become cooler as they near the bottom of said tubes. This will aid the 35 circulating of said products of combustion as the cooler gases will tend to raise the same upward in the chamber 30 and to the flue connection 32. As the water is drawn from the heater through the pipe 34 and 40 the fuel entering the combustion chamber 11 and being ignited by the pilot light therein heats the water which is in the fluid chamber 9, and such heated water being of a lesser specific gravity than the unheated 45 water entering the said fluid chamber by means of the supply pipe 41, it will rise and pass into the hollow interior 8 of the cover 7, and thus pass through the opening 33 and into the pipe 34 above the same, when the 50 water is being drawn. The rising of the warm water is also assisted by the pressure of incoming water. The heat from the combustion of the fuel in the combustion chamber and through the tubes 12 and chamber 55 30 will cause such parts to expand so that the heater body will be extended upward a slight amount when the parts become heated thereby. Since the rod 20 is of a non expanding metal and is covered with the insulating cover 22 to protect it from the heat 60 65

in said combustion chamber, such rod will not be affected by the heat from said chamber but will retain its ordinary length at all times. When the heater has become heated to a certain degree of temperature as fixed by experiment and as set by the adjusting screw 38' in the arm 39, the heater on expanding will raise the post 35 and will thus allow the free end 38 of the arm 37 to drop, whereupon the arm 39 will be released and 70 the spring 67 will raise the rod 64 and the valve 66, so that such valve will close the port 58, and thus shut off the flow of fuel through the valve casing 53 and the pipe 56, and into the burner 23. The casing 1 on 80 expanding will slowly close the port 58, as described, so that when the fluid being drawn from the heater is gradually getting warmer the valve 66 will be slowly rising and reducing the flow of fuel through said 85 port. In this manner the heater will have a perfect regulation so that as the fluid becomes warmer the supply of fuel for combustion becomes smaller, while as the water or other fluid becomes cooler the casing 1 90 will contract and thus open the port 58 by means of the fulcrum 36, which will tilt the arm 37, thereby raising the free end 38 thereof and drawing down the free end 39' of the arm 39, which will place tension on 95 the spring 67 in the valve casing 53, and thus draw the rod 64 and valve 66 downward to open said port. The post 35 on the cover 7 acts as a fulcrum for the arm 37 and the fulcrum 40 carrying the arm 39, will act as a multiplier for the regulation at the free end 39' of the arm 39, in that the heater contracts both the post 35 and fulcrum 40 will drop downward on account of both being fixed to the same cover 100 7, as the rod 20 is of a non expanding metal and retains its original height the free end 39' of the arm 39 will be lowered just about twice the distance it would if a single arm and fulcrum were used. 110

It will readily be seen that with my improved form of instantaneous water heater the arrangement of the parts and system of the same is such that both the cool water and cool gases are in the bottom of said heater while the heated products of combustion and heated water are at the top of the same. The advantage derived from this is that the natural tendency of both heated water and gases is to rise, and the operation 115 of the heater will be more efficient thereby. 120

What I claim as my invention and desire to secure by Letters-Patent is—

The combination with a water heater having a water valve and thermostatic means, of a valve casing having a single partition within the same, a port in said partition, a seat on each side of said port, a valve on one side of said partition, said valve normally engaging one of said seats and being 125 130

adapted to be automatically opened and closed by said water valve, and a valve on the other side of said partition and normally extending outward from the other seat and 5 adapted to approach said seat as the water in said heater increases in temperature to regulate the admission of gas through said valve, and to engage said seat and close said

port when said temperature becomes excessive.

In testimony whereof, I the said JOHN P. REINECKE have hereunto set my hand.

JOHN P. REINECKE.
